UNITED STATES PATENT OFFICE.

LOREN RISK, OF OELWEIN, IOWA.

AUTOMATIC LINE-SPACER.

No. 834,323.

Specification of Letters Patent

Patented Oct. 30, 1906

Application filed April 4, 1906. Serial No. 309,926.

To all whom it may concern:

Be it known that I, LOREN RISK, a citizen of the United States, residing at Oelwein, in the county of Fayette and State of Iowa, have invented new and useful Improvements in Automatic Line-Spacers, of which the following is a specification.

My invention pertains to improvements in what may be termed "line-spacers."

10 It has for its object to accomplish that end in a simple, expeditious, and effective manner; and it therefore consists of the features substantially as hereinafter fully disclosed, and particularly pointed out by the claims.

15 In the accompanying drawings, illustrating the preferred embodiment of my invention, Figure 1 is a plan view thereof. Fig. 2 is a side elevation of the same. Fig. 3 is a vertical longitudinal section produced 20 through the spacing-finger-actuating bar or rack. Fig. 4 is a corresponding section taken through the spacing-bar-carrying slide and adjunctive parts. Fig. 5 is a transverse section taken through said slide and its manu- 25 ally-moved contrivance. Fig. 6 is an enlarged detached perspective view of the finger-actuated bar or rack. Fig. 7 shows disassembled detached views of the locking-nuts for controlling the extent of the movement of 30 the rack-bar. Fig. 8 is also a detached perspective of the contrivance for manually manipulating the rack-bar-engaging pinions. Fig. 9 is a transverse section produced through the point of connection between the spacing- 35 finger-attaching stem or post of the aforesaid slide or carriage.

In carrying out my invention I provide in connection with a suitable copy-holder, designated generally as 1, preferably of my own 40 devising and which may form the subject-matter of a separate application, a fixed longitudinal rack or track 2. Said rack or track is connected, preferably as shown, by end brackets 3, to said holder as to occupy a 45 plane or position below the latter, and arranged in a plane above and a little laterally of said track or rack is a second rack or bar 4, with its cogged or rack surface facing downwardly or in a direction opposite to that in 50 which the rack or track 2 faces. Said rack or bar 4 is supported near one end in an arm 5, secured to one of the brackets 3, and near its other end in an aperture 6, produced in the other of said brackets. Said bar has secured to its end extending beyond the latter bracket a spring 7, the opposite end of which

being for convenience secured upon one end of the track 2 and by a fastening means common to both said spring and track, the tension thereof being exerted to impart endwise 60 thrust to said bar, and opposed to which tension is a pin or stop 8, projecting from said bar and standing normally in contact with one of the brackets 3. The arm 5 has its free end provided with opposite pendent 65 flanges 9, between which is received and slides one end of the bar 4, which end of the latter is split or slotted horizontally, as at 10, to receive said end of said arm and permitting such sliding movement of said bar. The 70 opposite end of said bar has sleeved or inserted thereon jam-nuts 12 13, engaging screw-threads 14, formed upon the corner edges of the bar 4. It is observed that by the requisite manipulation of said nuts their 75 position may be readily adjusted for varying the stroke of the spacing-finger-controlling bar 4, according to the extent of space over which it may be desired to move said finger, as will be readily appreciated. Said bar or 80 rack 4 is equipped at its extreme rear end with an upstanding fixed finger-piece 16 for its convenient actuation.

A slide or carrier 17, which may be of the form or character shown, is mounted to be 85 freely moved upon parallel guide-rod 18, passing therethrough and fixed to the brackets 3, and upon a suitably-equipped stem or post 19, carried by said slide or carrier, is a spacing-finger 20, adapted to extend across 90 and rest upon the leaves of the memorandum book or other matter which may be placed upon the holder 1 and from which it may be required to copy notes. Of course the spacing-finger is designed to immediately under- 95 lie the line of matter or stenographic notes it may be desired to be copied. Said stem or post 19 is inserted into a vertical socket or aperture 19, extending through the slide 17, and is provided with a set or holding screw 100 20', screwing into a horizontal threaded aperture 21, intercepting said aperture or socket 19 and engaging or impinging said stem for its retention in place. Said slide or carrier has also freely passing horizontally 105 therethrough a hand-wheel-equipped shaft 22, which has fixed thereto two fine toothed or cogged pinions 23 24, engaging the rack-bars or tracks 2 4, respectively, one, however, being of a greater diameter than the 110 other and arranged or connected for conjoint action, as presently seen. The smaller pin-

ion 23, which is actuated as the manually-actuated bar 4 is operated, has a slip-ratchet coupling or connection 25 with the larger pinion 24, which travels upon the track 2, and the interacting ratchet-faces of said ratchet connection 25 between the two pinions are rendered capable of such slip connection or engagement by means of a spring-pawl arrangement 26 as the manually-actuated bar 4 is released. The shaft 22 is also equipped with a spring 27, interposed between the slide 17 and the pinion 24, and whereby by pulling outward upon the hand-wheel of said shaft said spring may be duly compressed and the pinions 23 24 be thus moved laterally or outward, thereby permitting the disengagement of these pinions from their rack-bars. This adjustment of parts permits the quick returning of the finger-bearing slide or carrier to its initial position when the latter has been moved to its final position. Said spring 27 permits the automatic lateral movement or return of the pinions to their normal position when outward lateral pressure is removed from the shaft 22, bearing said pinions, as is apparent.

It is noted that when it may be desired to move the spacing-finger 20 over the page of the memorandum-book for the guidance of the copyist it is only required that the requisite pressure of the finger be applied to the piece 16 when the rack 4 will be moved rearward, which will of course engage and partially turn its engaging pinion 23 and accordingly, through the pinion 24, traveling upon the track or rack 2, transmit movement to the carrier or slide 17, in turn effecting the adjustment of said spacing-finger 20.

The various other adjustments of the several parts of my invention are apparent from what has already before been stated, it is believed.

It will be apparent in operation that the copyist's note-book being suitably held in place upon the holder 1 by means not shown, and so that the lining or spacing bar 20 may just underlie the initial line of matter for transcribing or copying, as well understood, said initial line of matter having been copied the operator suitably presses the finger-piece 16, whose engagement with the rack-bar 4 actuates the gearing, transmitting movement to said spacing-bar, accordingly moving the latter so as to take a position just under the next line below, this actuation of parts being repeated at the required intervals throughout the copying operation until the entire page of the note-book has been copied. The manipulation of the requisite parts, as at 23, &c., is now resorted to, as above noted,

to permit the returning manually of the spacing-bar 20 to its initial position, as is readily appreciated, when of course another leaf or page of matter may be turned over and brought under the spacing-bar and the copying thereof be proceeded with, and so on.

I claim—

1. A device of the character described, comprising practically opposed racks, one adapted to be manually actuated, a slide or carrier suitably mounted in position, pinions adapted to engage said racks respectively, means carrying said pinions from said slide and a spacing-finger carried by said slide.

2. A device of the character described, comprising opposed racks, a manually-actuated rack; stroke-controlling means therefor, a slide carrying a spacing-finger, and pinions engaging said racks respectively, and means carrying said pinions from said slide.

3. A device of the character described, comprising opposing racks, one equipped with a manually-actuated finger-piece, a spring adapted to deliver its pressure upon the manually-operated rack, pinions engaging said racks respectively, a slide carrying a spring-finger, and a shaft carried by said slide and bearing said pinions.

4. A device of the character described, comprising opposed racks, one equipped with means for its manual actuation, a slide carrying a spacing-finger, pinions engaging said racks respectively, and having a "slip-ratchet" connection therebetween, and a shaft bearing said pinions and carried by said slide.

5. A device of the character described, comprising opposed racks, one adapted to be manually actuated and equipped with stroke-controlling jam-nuts, a slide carrying a spacing-finger, pinions adapted to engage said racks respectively, and a shaft carried by said slide and bearing said pinions.

6. A device of the character described, comprising opposed racks, one adapted to be manually actuated and held under spring-pressure, a slide carrying a spacing-finger, pinions adapted to engage said racks respectively, means for throwing said pinions out of normal position and a shaft journaled in said slide and equipped with a spring delivering its tension to automatically restore said pinions to normal position.

In testimony whereof I affix my signature in presence of two subscribing witnesses.

LOREN RISK.
